CLAIM

The ornamental design for a webbing clip, as shown and described.

DESCRIPTION

FIG. 1 shows a perspective view of my design for a webbing clip;

FIG. 2 is a front view thereof;

FIG. 3 is a back view thereof;

FIG. 4 is a top view thereof;

FIG. 5 is a bottom view thereof;

(Continued)

FIG. 6 is a side view thereof; and,
FIG. 7 is another side view thereof.

1 Claim, 2 Drawing Sheets
